(57) **CLAIM**

The ornamental design for a blade information handling system chassis bezel, as shown and described.

DESCRIPTION

FIG. 1A is a front perspective view of the blade information handling system chassis bezel comprising the present invention;

FIG. 1 is a front perspective view thereof showing the bezel in an open position;

FIG. 2 is a front view thereof;

FIG. 3 is a left side view thereof;

FIG. 4 is a right side view thereof; and,

FIG. 5 is a top plan view thereof.

The broken line showing of the blade information handling system chassis is included for the purpose of illustrating unclaimed environmental structure and forms no part of the claimed design.
